HIRAM BROWN, OF LOWELL, MASSACHUSETTS.

Letters Patent No. 81,834, dated August 25, 1868.

IMPROVEMENT IN EXCAVATORS.

The Schedule referred to in these Letters Patent and making part of the same.

TO ALL WHOM IT MAY CONCERN:

Be it known that I, HIRAM BROWN, of Lowell, in the county of Middlesex, and State of Massachusetts, have invented certain new and useful Improvements in Excavators for removing earth or other substances, of which the following is a full, clear, and exact description, reference being had to the accompanying drawings, making part of this specification, in which—

Figure 1, sheet 1, represents a side elevation.

Figure 2, sheet 2, a plan or top view.

Figure 3, sheet 3, a transverse section on the line A Z of fig. 1 or 2.

Figures 4 and 5, on sheet 4, represent each a top view of the jointed double scoop or excavating device, the former as closed, and the latter as opened.

Figures 6 and 7, on sheet 3, represent each an end view of the double scoop, the former, which is shown as closed together, and elevated as when filled and ready to discharge its load, and the latter opened and in position to scoop up earth, or load itself by being drawn together, and then upward, it being in its present position shown as partly embedded, or sunk, or driven into the ground, to be filled or loaded by drawing the two parts or scoops together, as shown in fig. 6.

Figure 8 is a side view of the arms G in fig. 6, and the rod H, which connects them.

Figure 9, a bottom view of the excavator.

This invention relates to that kind of excavator or apparatus used for removing earth, which is called self-loading or self-filling, and has for its object to avoid the necessity of shovelling to fill the excavator, or an unnecessary expenditure of power to cause it to fill or load itself.

In constructing my invention, the jointed double scoop or excavator is made in two parts, A A being the ends, and B B the curved sides, which have each a projecting flange or lip, n, at the top for opening the apparatus.

Curved arms C are secured to the upper and inner or adjoining portions of the ends A, and extend upward and outward, as shown. These arms are jointed together by a shaft or rod, D, which passes through the arms, and are secured by nuts m, screwed on to the ends of the rod, thus forming a hinge or joint, on which the double scoop is closed or opened.

To the lower edge of each of the curved sides B, which do not extend to the bottom, teeth or prongs l are secured, to facilitate the filling action of the excavator, when the parts are drawn together, and to prevent any difficulty caused by stones or cobbles which might come in the way.

To lift and close the double scoop or excavator, a yoke, E, is sometimes employed, the curved arms, k, of which, or a roller, g, on each of said arms, engages with the under sides of the arms C, to lift or draw the latter arms together, close the excavator, and draw it upward.

A curved plate, F, secured to the ends of the arms k, outside of the arms C, retains the yoke on the latter arms. Instead of the yoke E for lifting and operating the excavator, I sometimes employ additional arms, G, which are jointed or pivoted to the outer ends of the arms C, and jointed or hinged at their top ends by a rod or shaft, H, which extends from one pair of such arms to the other, and through their ends, where it is secured by nuts h.

Connecting or hoisting-rings a rise from the tops of the yokes E, and similar rings from the top of the rod H, and the hoisting or elevating-apparatus connects with said rings.

This improved self-loading excavator may be operated by a windlass, or any other suitable machinery or apparatus, where power can be applied, by hand, or by a steam-engine, or other motive-power, and according to the nature or the kind of work to be done.

To illustrate one method of operating this excavator, a suitable framework may be constructed with posts I, connected and supported by braces J, beams K, and cross-girts L, all well fastened together. On the tops of the beams K, rails or rods, b, are arranged and secured, and a carriage is placed on these rails. The wheels of the carriage are grooved to keep them on the rails. Longitudinal girts N extend from one axle, O, of the carriage to

the other, where they are well fastened. A grooved chain-wheel, P, is arranged to rotate in bearings R, above the girts N, and said chain-wheel comes between the two girts. On one end of the chain-wheel shaft a ratchet-wheel, S, is firmly fastened, and a pawl, d, pivoted to one of the girts N, engages with the teeth of the ratchet-wheel.

A spring, 4, attached to the lower end e of the pawl, and to the girt N, holds the upper end of the pawl in contact with the teeth of the wheel S.

A hanger, S, depends from each of the girts N, and the lower end of each hanger is turned inward, forming a lip or projection, e, for opening and suspending the excavator, as seen in figs. 1 and 3, the lip e engaging with the flange n on the top edge of each of the curved sides B of the excavator, to open the latter by allowing its entire weight to bear on the above-described suspending and opening-devices.

One end of a chain, or a rope, T, is connected with the top of the yoke E, or to the rings a of the same, or such rings on the rod H which connects the arms G. Said chain passes over the wheel P, and downward to the windlass U, which is intended for hoisting the excavator. This windlass is geared to a crank-shaft above it, arranged and provided with a crank, V, for operating the windlass to hoist the excavator.

When the excavator is elevated and ready for operation, it is retained in that position, as clearly shown in figs. 1 and 3, by the hangers S, as before described, and curved springs f hook over the ends of one or more of the arms C, to prevent the excavator closing when released from the hangers.

This releasing of the excavator, so as to allow it to fall or be lowered, is effected after slackening the hoisting-chain, by hauling on the squaring-lines W, connected with some part of the excavator.

This hauling action, in two different directions torsionally, releases the excavator from the lower projections e, and it falls to the ground ready to be drawn together to fill or load itself, and about as shown in fig. 7. The windlass, or other hoisting-device or apparatus, is then brought into action, and the arms C drawn together, and the excavator filled and hoisted to the desired height, when the carriage may be run in either direction on the rails b, to and over a car or cart, or a cart or wagon may be backed or drawn under the filled excavator, to receive the contents taken up by the same.

To discharge the contents of the excavator, the lips or projections e and n are brought together, as shown, and the chain T slackened by tripping the pawl d, and by turning back the windlass, the excavator will then open, as shown in fig. 8, and discharge its load into any cart or car beneath it.

The pawl d is tripped or disengaged from the teeth of the ratchet-wheel S, by a cord or line, Y, attached to the lower end e of the pawl, and leading to some convenient place for operating.

This improved excavator may be used with a derrick, on a swinging boom, or on any hoisting-device used on a car or other wheel vehicle, or on a floating scow or boat, for excavating in docks or harbors, and beneath the surface of water; and when used as last described, the curved sides B may extend to the bottom of each part of the excavator, and leave no great opening, Z, as between V V in fig. 9, where the prongs l, on one side, pass between those on the other.

The beams K may be extended to any reasonable length, and by detaching the chain from the windlass, or by disconnecting said chain somewhere between the windlass and the chain-wheel P, the carriage on the tops of the beams K may be run a greater distance with the loaded excavator, as where earth is removed on the borders of a railroad, and on dumping-cars, running on transverse tracks, elevated above and extending from over the regular track, or a side-track, to some distance from freight-cars set on the side or other track, to receive the earthy substance from the car on the transverse track.

Here my improved excavator would take the place of the dumping-car on the transverse track, which may be represented by the rods or rails b, and the beams K, and no shovelling need be performed to load the excavator, and remove the earthy substance to the transporting-cars.

Having fully described my invention, its nature and its uses, what I claim, and desire to secure by Letters Patent, is—

The scoops A B, with the lips n, in combination with the arms G and yoke E, when used in connection with the movable carriage, with hangers S and wheel P, ratchet S and pawl d, all constructed and arranged substantially as described, and for the purpose specified.

HIRAM BROWN.
